UNITED STATES PATENT OFFICE.

WILLIAM WESLEY HICKS, OF SAN FRANCISCO, CALIFORNIA.

DESIGN FOR AN ELECTRIC HEATER.

Application filed May 18, 1925. Serial No. 13,473. Term of patent 14 years.

To all whom it may concern:

Be it known that I, WILLIAM WESLEY HICKS, a citizen of the United States, and a resident of the city and county of San Francisco, State of California, have invented a new, original, and ornamental Design for an Electric Heater, of which the following is a specification, reference being had to the accompanying drawings, forming part thereof.

Figure 1 is a front elevation of an electric heater; and

Fig. 2 is a plan view thereof.

I claim:

The ornamental design for an electric heater, substantially as shown.

WILLIAM WESLEY HICKS.
